(57) **CLAIM**

The ornamental design for a fishing lure retrieval device, as shown and described.

DESCRIPTION

FIG. 1 is a front perspective view of a first embodiment of the fishing lure retrieval device of the present invention; FIG. 2 is an enlarged, fragmentary, front, perspective view thereof, particularly showing an eyelet screw mounted in the front end thereof;

FIG. 3 is a rear perspective view thereof;

FIG. 4 is a right side elevational view, the left side view being a mirror image thereof;

FIG. 5 is a top plan view thereof, the bottom plan view being a mirror image thereof;

FIG. 6 is a front elevational view thereof;

FIG. 7 is a rear elevational view thereof;

FIG. 8 is a front perspective view of a second embodiment of the fishing lure retrieval device of the present invention; FIG. 9 is an enlarged, fragmentary, front, perspective view thereof, particularly showing a clip mounted in the front end thereof;

FIG. 10 is a rear perspective view thereof;

FIG. 11 is a right side elevational view, the left side view being a mirror image thereof;

FIG. 12 is a top plan view thereof, the bottom plan view being a mirror image thereof;

FIG. 13 is a front elevational view thereof; and

FIG. 14 is a rear elevational view thereof.

FIG. 15 is a right side elevational view of a third embodiment of the fishing lure retrieval device with net, the left side being a mirror image thereof;

FIG. 16 is a top plan view thereof; the bottom plan is a mirror or image.

FIG. 17 is a rear elevational view thereof.

FIG. 18 is a front elevational view thereof; and,

FIG. 19 is a fragmentary, top, right side perspective view thereof, particularly showing the fishing net.
